UNITED STATES PATENT OFFICE

2,531,984

ROLLER UNIT FOR FURNACES

William James Millar, London, England, assignor
of one-half to Electric Resistance Furnace
Company Limited, London, England, a com-
pany of Great Britain

Application July 17, 1947, Serial No. 761,518
In Great Britain January 11, 1943

Section 1, Public Law 690, August 8, 1946
Patent expires January 11, 1963

4 Claims. (Cl. 198—127)

1

This invention relates to a roller unit for furnace conveyors.

The invention has for its primary object to provide an improved arrangement and construction of roller unit, which is of particular utility for furnaces of considerable lateral width, whereby difficulties resulting from distortion of rollers under the high temperature involved may be avoided.

More specifically, the invention has for its object to provide an improved roller unit extending transversely of the furnace chamber and constituted by a number of axially spaced individual rollers independently mounted in suitable bearing means and mechanically coupled together and to a driving shaft by coupling means, such as muff couplings.

The invention is hereinafter described by way of example with reference to the accompanying diagrammatic drawings, in which:

Fig. 1 is a view in front elevation, partly in section, illustrating a roller unit constructed in accordance with the invention;

Fig. 2 is a side elevation showing one arrangement for driving a number of roller units in unison, and

Fig. 3 is a sectional plan view showing the arrangement of the driving means in relation to the furnace.

Referring particularly to Fig. 1, each roller unit extending transversely of the furnace comprises a roller 1 adjacent to one side of the furnace, and one or more rollers 2, axially spaced from the roller 1, each of the rollers being fixedly mounted on a short spindle 4 mounted in suitable bearings 5. The spindle 4 of each roller is provided with extensions 6 at each end which are of square cross-section and project beyond the bearings 5. Adjacent axially spaced rollers are mechanically coupled together by coupling means, such as muff couplings 7 each of which comprises a metal bar or rod 8 provided at each end with a socket or head 9 having a recess of square cross-section to engage the corresponding extension 6 of the respective spindle 4.

At the driving end of the unit the outer extension 6 of the adjacent roller spindle 4 engages the socket or head 10 of a coupling bar or rod 11 which extends through a passage 24a in the insulated wall 24 of the furnace, and at its outer

2

end is provided with a socket or head 12 for engaging a square extension 13 of a driving spindle 14. This driving spindle 14 is at its outer end fitted with a driving sprocket 15 and is mounted in a bearing unit 22 supported externally in the furnace, for instance, by bolting to joists 23a with the intermediary of a plate 23 of asbestos or other heat-insulating material. The bearing unit 22 is provided with a boss 22a for the driving spindle 14 and also with bosses 22b for the support of stub shafts 17a on which jockey pulleys 17 are mounted. As shown in Fig. 2, the bearing units 22 may be shaped so as to fit closely together and may be in the form of interchangeable units, only certain of the bosses 22b being utilised as required.

An endless chain 16 engages the upper portion of each sprocket 15 and is maintained in operative relation thereto by means of jockey wheels or pulleys 17. The chain 16 passes around a driving sprocket 18 mounted on a shaft 18a (Fig. 3) which is adapted to be driven from an electric motor 20, for instance, by means of a belt drive 20a to a gearbox 19 having a shaft 19a from which the shaft 18a is driven by means of a belt 19b. A jockey wheel 21 is provided for adjusting the tension of the chain 16 as required, said jockey wheel 21 having its spindle carried by an arm 25 and adjustable in a slot 25a in an arm 25b, said arms 25, 25b being mounted to swing on the stub axles 17a carrying the adjacent jockey wheels or pulleys 17.

What I claim and desire to secure by Letters Patent is:

1. A roller unit for a furnace conveyor comprising a number of axially spaced rollers, a separate spindle for each of said rollers, an independent bearing for each spindle, said bearings being axially aligned with said spindles and the ends of each spindle being carried in the bearing associated therewith, a driving spindle in axial alignment with said roller spindles, and independent coupling members, axially aligned with said spindles and extending respectively between said bearings and adapted to couple said roller spindles together in axial alignment, and a coupling member adapted to couple the end spindle with said driving spindle.

2. A roller unit according to claim 1 wherein

said driving spindle forms an axial extension of said roller spindles.

3. A roller unit according to claim 1 wherein the ends of said roller spindles are of non-circular cross-section and said coupling members engage said ends of non-circular cross-section.

4. A roller unit according to claim 1 wherein the ends of said spindles are of square cross-section and said coupling members comprise rods having ends which are correspondingly recessed to engage said ends of square cross-section.

WILLIAM JAMES MILLAR.
